UNITED STATES PATENT OFFICE.

AUSTIN E. MILLER, OF SPRAGUE, WASHINGTON.

TRICYCLE.

SPECIFICATION forming part of Letters Patent No. 471,770, dated March 29, 1892.
Application filed September 2, 1891. Serial No. 404,523. (No model.)

To all whom it may concern:

Be it known that I, AUSTIN E. MILLER, a citizen of the United States, residing at Sprague, in the county of Lincoln and State of Washington, have invented a new and useful Tricycle, of which the following is a specification. This invention relates to velocipedes, and more especially to that class thereof known as "tricycles;" and the object of the same is to effect certain improvements on the device for which Letters Patent No. 438,273 were granted to me October 14, 1890.

To this end the invention consists, essentially, in the improvements in general construction on the patented machine referred to, as well as in the adjunctive and specific details and auxiliaries which tend to enhance the value and perfect the operation of the completed tricycle, all as hereinafter more fully described and claimed, and illustrated on the two sheets of drawings, wherein—

Figure 1 is a side elevation of my improved tricycle complete, the rear seat being shown in dotted lines as raised to permit the application of a basket, also in dotted lines. Fig. 2 is a plan view, part of the frame above the front fork being broken away. Fig. 3 is a vertical transverse section taken on a line just in rear of the axle and looking toward the front. Fig. 4 is a perspective detail of the guiding mechanism. Fig. 5 is a cross-section through the front seat, looking to the rear and showing the driving mechanism as tilted. Fig. 6 is a central longitudinal section through the driving mechanism.

Referring to the said drawings, the letter F designates the frame-work of this improved machine, which has journals for the main axle A, on which are mounted the main wheels W W', and for the front fork, which supports the steering-wheel w. G is the guiding mechanism, which is connected with said front fork and which is useful for guiding or steering the machine.

L are the levers by which the machine may be propelled by an operator.

D is the driving mechanism, wherein power may be stored by hand or by the running of the machine downhill, which mechanism is controlled by shifting devices S for throwing it out of or into connection with the main axle, and B is a basket or other receptacle,

which is removably connected with the frame and which is useful for carrying packages and the like under the circumstances herein-after named. These various features of my improved tricycle combine to produce the complete machine and are preferably used in connection with each other, although I reserve the right to make such changes therein and elaborations thereof as may come within the spirit of my invention, and the detailed constructions of said features are preferably as follows:

The frame-work F of this machine is preferably of metallic tubing for the sake of lightness and strength, and the various parts thereof are removably and adjustably connected, as is usual in this class of machines and as is illustrated in the drawings. Said frame-work comprises a circular portion 1, bearing at its rear end an upright 2, to which is pivotally connected the rear seat or saddle 3, bearing at opposite sides uprights 4, whose lower ends have ball-bearings 5 for the main axle A and whose upper ends are socketed, as at 6, for a purpose to appear hereinafter, and bearing at its front side a forward extension 7, having uprights 8, to which the levers L are pivoted and also to which the front seat or saddle 9 is connected, the front end of this extension 7 carrying the front fork. The said axle A is provided with two cranks 10 near its center and oppositely disposed, and just inside the bearings 5 it is provided with two small gears 11 and 12, which are keyed on the axle. The driving-wheel W is on the right side of the machine adjacent to the gear 11 and is keyed to the axle, while the other large wheel W' is on the opposite side of the machine and is mounted loosely on the axle, so as to permit its independent turning while the tricycle is rounding curves. The front fork 13 carries the steering-wheel w and is journaled in bearings 14 at the front end of the extension 7. On the shaft of this fork is a gear 15, which intermeshes with a toothed segment 16, mounted at the lower end of a bar 17, and the upper end of this bar is rigidly connected with a rod 18, which passes rearwardly through suitable bearings 19 and is turned up at its rear end.

The guiding mechanism G (best shown in Fig. 4) consists of a metallic plate 20, which

forms the back for the front seat 9 and has at its center a rearwardly-turned ear 21, which is perforated, so as to pass over the upturned end of the rod 18, and is adjustable thereon 5 by a set-screw 22.

23 is a belt adapted to encircle the waist of a rider sitting on the front seat, and this belt passes through eyes 24 in the ends of the seat-back, between which eyes it passes behind 10 said back and beneath the ear. 26 are straps rising from this belt at its sides and adapted to pass over the shoulders of said rider; but the use of these straps is optional, their employment obviating the necessity for the set-screw, because the belt and back will be supported by them. The said rider, sitting on the front seat and leaning against the back, can, by swaying his body slightly to one side or the other, oscillate the rod 18, so as to swing 15 the toothed segment 16, and this motion will turn the gear 15 and with it the front fork 13 and the steering-wheel *w*.

The propelling mechanism by which the machine may be driven by the operator consists 25 of the levers L, which are constructed as follows: 30 is the body of the lever, which is bent slightly between its ends where it is pivoted, as at 31, to the upright 8, and its upper end 32 is formed into a handle.

30 33 is a pitman-rod whose rear end has a bearing which embraces one of the cranks 10 of the axle A, whose front end is pivoted at 34 to the lower end of the lever 30, and whose front extremity 35, forward of said pivot, is 35 turned outwardly, so as to form a pedal, there being of course one of such levers and its connection at each side of the machine, and the levers operating oppositely by reason of the opposite disposition of the cranks 10 on the 40 axle A. By this construction the operator has a chance to draw inwardly on one handle and simultaneously push on the pedal at that side of the machine and on the other handle, thus giving him an opportunity at two points 45 during each revolution of the axle of applying power thereto in three ways at once, and this is especially permitted by the improved guiding mechanism above described, which does not occupy the rider's hands, as is so 50 common in machines of this class.

The driving mechanism D is useful for the purpose of assisting in the propulsion of the machine, especially when it is heavily laden or when it is moving over rough ground or up 55 a hill, and this mechanism is constructed as follows: Pivoted in the lower ends of the rear upright 2 and of a similar upright 2', beneath the extension 7 of the frame, is a horizontal supporting-bar 40, which passes over the center of the axle A, and journaled in this bar is a vertical shaft 41, whereon is keyed a large gear 42, which is adapted to mesh with the small gear 11 or 12 or with neither, according as this shaft is moved laterally of the machine 60 at its upper end. Mounted in the sockets 6 at the upper ends of the side uprights 4 of the frame is a cross-plate 43, having a longi-

tudinal slot 44 at its center, in which is loosely mounted a bearing 45 for the upper end of this shaft, the said bearing being prevented 75 from rotation by its engagement with the slot 44, and having at its lower end teeth 46, intermeshing with similar teeth at the upper end of a tube 47, which surrounds and is secured on the shaft 41.

75 48 is a spiral spring whose inner end is secured to the tube 47 and which stands just above the large gear 42, and the outer end of this spring is connected with a plate 49, that depends from the edge of a disk 50, which is 80 journaled on the bearing 45.

51 is another spring standing above the first and just beneath the disk, the outer end of this spring being connected with said plate 49 and its inner end with said bearing. The 85 latter slides on the vertical shaft 41 and is borne normally downward by a spring 52, which is interposed between the upper end of the bearing and a bracket 62, described below, and 55 is a crank-handle adapted to be connected with the upper end of the vertical 90 shaft, as shown. By this means the handle may be rotated in the proper direction to turn the large gear 42 when it is out of mesh with both the small gears, and as it turns it winds 95 the inner end of the spring 48 upon its tube, while the outer end of this spring, being connected by the plate 49 with the other spring 51, winds the latter around the said bearing, and a retrograde movement of the gear is prevented by the intermeshing of the ratchet-teeth between the adjacent ends of the tube and the bearing, this intermeshing being caused by the spring 52 pressing the toothed 100 end of the bearing against the toothed end of 105 the tube, as best seen in Fig. 6.

When the machine is descending a hill, if the large gear be engaged with the left small gear 12 the rotation of the axle will cause the turning of the large gear and its vertical shaft 110 in the same direction, whereby power will be stored in the springs the same as if it had been done manually by turning the crank.

When it becomes necessary or desirable to throw the driving mechanism D into use, the 115 vertical shaft is canted in the opposite direction, whereby the large gear is caused to mesh with the left small gear 11, and at this time the unwinding of the springs and the expenditure of their stored power will assist the operator; but it will be obviously necessary to provide means for disengaging said adjacent ends of the tube and bearing, and this I preferably accomplish automatically in the manner described below.

125 The shifting mechanism S (best seen in Fig. 5) comprises a shaft 60, extending longitudinally of the machine and journaled in a bearing 61' in the upper end of the upright 2' and in another bearing 61, depending from the cross-plate 43. A bracket 62, (above mentioned,) which rises from the rear end of this shaft, turns to the rear and is provided with a bearing for the upper end of the vertical

shaft 41. An operating-handle 63, extends from the said shaft 60 to one side of the front seat 9 alongside a rack 64, having three notches, and with its outer end preferably turned forward, as seen in Fig. 2, and a catch-lever 65, pivoted to said handle, with its tip 66 adapted to engage one of the notches in the rack and its body borne by a spring 66 normally into engagement therewith. By this means, when the said handle 63 is drawn upwardly and its catch engaged with the uppermost notch in the rack, the bracket 62 will be thrown to the left, as will the upper end of the vertical shaft 41, and the large gear will be engaged with the left gear 12 on the axle A. When the handle is moved down, the gear will be in mesh with the other gear 11, and when the handle stands over the center notch in the rack the large gear will be out of engagement with both small gears. In the latter position the vertical shaft may be rotated by hand by its crank 55; but when said shaft is inclined to either side it is obvious that it is desirable to have the teeth at the meeting ends of the tube and bearing thrown out of engagement, and this I preferably accomplish automatically in the following manner: On the upper side of the cross-plate 43 at each side of its slot 44 is an enlargement 70, depressed at its center, as at 71, and the upper end of the bearing 45 is provided with a transverse bar or with two projections 72, adapted to ride up the inclined inner faces of the enlargements 70. Hence when the shaft 41 stands truly vertical these projections 72 rest in the depressions 71, the expansive force of the spring 52 assisting, and the teeth at the adjacent ends of the bearing and tube are thrown into engagement; but when said shaft is tilted to either side the projections 72 are caused to travel up the inclined faces of the enlargements 70 at the side of their depressed centers, and therefore the bearing is automatically drawn upwardly on the shaft against the expansive force of the spring 52, so as to disengage its teeth 46 from those at the upper end of the tube 47. Thereupon the action of the coiled springs 48 and 51 in automatically uncoiling is prevented by the engagement of the large gear with one of the small gears on the axle.

The basket B may be of any approved pattern and of metal, wood, or other material. From the lower end of the rear upright 2 an arm 80 extends rearwardly and curves upwardly, and its upper end is provided with an eye 81, and the basket is provided with two ears 82, adapted to embrace said eye and perforated for the reception of a fastening pin, the lower end of the basket being preferably also notched, as at 85, so as to fit over the body of this arm. By this means the basket is rendered detachable from its point of support and connection with the machine. When the basket is in place and filled or partially filled, it is supported at the point best suited for it and partially counterbalances the weight

of a single rider; but when there are two riders the basket is removed and the rear seat 3 is turned down, as seen in full lines in Fig. 1, 70 the weight of the rider thereon then counterbalancing the weight of the front operator.

86 are brackets, which may be detachably connected by screws, bolts, or pins 87 with the cross-plate 43, and the ends of these brackets carry skeleton baskets 88, which may receive light or small parcels.

Other brackets and supports may be provided at various parts of the frame for carrying parcels or receptacles for containing the 80 same; but I prefer to use the basket B principally for this purpose on account of its location.

There are certain details of construction which I have not specifically described, but 85 which are shown in the drawings, and it is to be understood that there are elaborations and modifications which may be made to a considerable extent without departing from the spirit of my invention. I may suggest that 90 this latitude and scope for the ingenuity of the manufacturer in turning out a practical machine of the class described is perhaps wider in velocipedes than in many other devices. For instance, the specific construction 95 and shape of the frame, the style of the bearings, the materials and proportions of parts, the tires, rims, and spokes of the wheels, the form of pedals, and the nature of the saddles employed have no material effect upon the 100 present invention, except that they enhance the value of the completed machine and combine in producing a beautiful and practical whole. The utility and operation of the device has been described in connection with its 105 various elements and its uses and advantages are thought to be obvious.

Although I have not shown it, I preferably provide the bearing 45 and projections 72 with anti-friction rollers or balls, which travel easily 110 in the slot 44 and over the enlargements 70, whereby the shifting of the machine will be rendered easy. The machine is especially adapted for a gentleman and lady, the latter sitting on the rear seat and facing to the rear. 115

What is claimed as new is—

1. In a velocipede, the combination, with the frame-work supported on wheels, a rear upright carried by said frame-work, and a saddle pivotally secured to said upright, of an arm 120 extending from said upright and a basket adapted to be detachably connected with and supported by said arm when the saddle is turned forward, as set forth.

2. In a velocipede, the combination, with the 125 frame-work supported on wheels, a rear upright carried by said frame-work, and a saddle pivotally connected to said upright, of an arm extending rearwardly from the lower end of said upright, turning upwardly, and having 130 an eye at its upper end, a basket adapted to fit between said arm and upright when the saddle is thrown forward, said basket having a notch engaging the body of said arm, and

- perforated ears on the basket, adapted to align with the hole in said eye for the reception of a fastening device, as and for the purpose set forth.
5. In a velocipede, the combination, with the frame-work supported on wheels, a fork journaled in said frame-work and carrying the steering-wheel, a gear on said fork, a rod journaled in bearings of the frame-work, a bar depending from said rod and having a toothed segment engaging said gear, and means for propelling the machine, the rear end of said rod being turned upwardly behind the rider's seat to form a back-support and guiding-arm, 10 of a seat-back having a rearwardly-projecting perforated ear loosely mounted on said upturned end and vertically adjustable thereon, a belt to firmly secure the body to said back secured to said back and adapted to encircle 15 the rider's waist, and shoulder-straps rising from said belt, as and for the purpose set forth.
4. In a velocipede, the combination, with the frame-work supported on wheels, a fork journaled in said frame-work and carrying the steering-wheel, a seat, a horizontal rod mounted in bearings of the frame-work with its rear end upturned behind said seat, and connections between said rod and fork, of a seat-back 20 having a rearwardly-projecting perforated ear 25 adjustably mounted on said upturned end, eyes at the ends of said back, and a belt whose center stands in rear of the back and passes forwardly through said eyes and whose body is adapted to embrace the waist of the rider, 30 as and for the purpose set forth.
5. In a velocipede, the combination, with the frame-work, an axle journaled in the rear end thereof and provided with oppositely-disposed cranks, a fork journaled at the front end thereof 35 of, wheels on said axle and in said fork, a seat, and guiding mechanism, substantially as described, for turning said fork, of two levers, each pivoted between its ends to the frame-work adjacent the seat, a pitman connecting the lower end of each lever with one of said 40 cranks, and a handle at the upper end and pedal at the lower end of each lever, as set forth.
6. In a tricycle, the combination, with the frame-work comprising a circular portion having a forward extension, a steering-wheel 45 therein, uprights at the sides of said circular portion, an axle journaled therein and carrying the supporting-wheels, and small gears on said axle, of a cross-plate detachably secured to the upper ends of said uprights and having a longitudinal slot, a supporting-bar pivotally mounted in uprights of the frame and 50 standing at right angles to said cross-plate and above said axle, a shaft stepped in said bar, a large gear thereon adapted to engage one of those on the axle when the shaft is tipped, a bearing sliding in said slot and embracing the body of said shaft, a coiled spring connecting said bearing and shaft, a disk supported by said bearing above the spring, a ratchet for preventing a retrograde movement of the shaft when it is vertical, but permitting it when it is inclined, and shifting mechanism, substantially as described, for moving the bearing in said slot, as and for the purpose set forth.
7. In a tricycle, the combination, with the frame-work, the axle carrying the supporting-wheels, small gears on said axle, an upright shaft stepped in an oscillating bar and having a large gear adapted to mesh with one of those on the axle, and a tube on said shaft, having ratchet-teeth at its upper end, of a cross-plate on the frame-work, having a longitudinal slot, upward enlargements at the sides of said slot, provided with depressed centers, a bearing in said slot, having lateral projections riding on said enlargements, the upper end of the shaft passing through said bearing and the lower end of the latter having ratchet-teeth, a coiled spring connecting the bearing and tube, an oscillating shaft, a bracket rising therefrom and embracing the upper end of said upright shaft, an expansive spring between said bracket and bearing, and shifting mechanism, substantially as described, for operating said oscillating shaft, as and for the purpose set forth.
8. In a device of the character described, the combination, with the frame-work, the axle carrying the supporting-wheels, a slotted cross-plate on the frame-work, a bearing therein, and a spring driving mechanism, substantially as described, whose shaft extends upwardly through said bearing, of an oscillating shaft, a bracket rising therefrom and embracing the upper end of said driving-shaft, a notched rack, a handle projecting from said oscillating shaft alongside the rack, and a spring-actuated catch connected to the handle and engaging the notches of the rack, all as and for the purpose hereinbefore set forth.
- In testimony that I claim the foregoing as my own I have hereto affixed my signature in presence of two witnesses.
- AUSTIN E. MILLER.
- Witnesses:
- C. H. NEAL,
T. J. BLEIMS.
